UNITED STATES PATENT OFFICE.

WILLIAM P. ROBERTSON, OF NEW YORK, N. Y., ASSIGNOR TO SHARP AND DOHME, A CORPORATION OF NEW JERSEY.

POISON-PROTECTIVE DEVICE.

1,091,441.

Specification of Letters Patent. Patented Mar. 24, 1914.

Application filed October 31, 1913. Serial No. 798,384.

To all whom it may concern:

Be it known that I, WILLIAM P. ROBERTSON, of New York, in the county of New York, and in the State of New York, have 5 invented a certain new and useful Improvement in Poison-Protective Devices, and do hereby declare that the following is a full, clear, and exact description thereof.

The object of my invention has been to 10 provide a device which shall prevent the accidental taking of poisonous pills and tablets, and to such ends my invention consists in the poison protective device hereinafter specified.

15 In the accompanying drawings—Figures 1 and 2 are perspective views of different embodiments of my invention showing the tablets provided with devices to prevent their being accidentally swallowed, the tablets being arranged in groups; and Figs. 3 and 4 are, respectively, perspective views showing single tablets of the form shown in Figs. 1 and 2.

Accidents frequently occur in which sickness or loss of life is caused by the taking 25 internally of a poisonous pill or tablet under the supposition that it is a different and harmless tablet, the kind of tablets thus most frequently taken by mistake being those 30 formed of bichlorid of mercury. So far as I know, no simple and effective means have yet been devised which will prevent such accidents, especially where the tablets are taken in the dark. I have invented a simple 35 means, and one which I believe to be most effective for the purpose of preventing such accidents.

40 My invention is capable of embodiment in many different forms and the illustrated embodiment is to be regarded as typical only, and my invention is not to be confined thereto.

Broadly, my invention consists in attaching 45 to the tablet a device to attract physical attention in case the tablet or pill is put in the mouth or dissolved in a glass of water. I shall call such device a label. In the embodiments illustrated in the drawings, such label takes the form of a thread or string 2 which, in the present instance, is embedded 50 in the tablets 1.

In the form of the invention shown in Fig. 1, the same thread passes through a

number of tablets and I have illustrated the threads as consisting of horizontal threads 3 55 and vertical threads 2, each tablet having both a horizontal and vertical thread passing through it. The tablets are thus formed into a group from which it is impossible to take one without severing the threads, 60 and thus even the sleepiest person would have his attention called to the fact that the tablet was one of a poisonous nature, assuming that only poisonous tablets were put up in this form. When a tablet is separated from the rest of the box it would, as 65 shown in Fig. 3, have the ends of the threads extending outside of it loosely, and if the tablet were put in the mouth in this form the sense of touch would very quickly reveal 70 the presence of the threads. Even if it be conceived that the tablet were entirely dissolved off the threads, the threads would reveal the nature of the tablet which had been dissolved and swallowed, and thus enable immediate relief to be applied. 75

In the form of my invention shown in Fig. 2, the tablets are simply connected by a single thread 2, and the appearance of a detached tablet is shown in Fig. 4.

The threads, being flexible, would not in the least interfere with the boxing or bottling of such pills or tablets and their medicinal qualities would not need to be interfered with or impaired in any manner, 85 whether the tablets were bottled or boxed, connected together, as shown in Figs. 1 and 2, or detached, as shown in Figs. 3 and 4.

It is evident that my invention will result 90 in the saving of many lives now lost through such accidents as those above mentioned.

By the terms "pill" or "tablet" occurring in the claims is meant a pill or tablet of a size small enough to be taken into the mouth or swallowed.

I claim—

1. The combination of a pill or tablet, and a physically separate label attached thereto.
2. The combination of a pill or tablet and a flexible label attached thereto.
3. The combination of a pill or tablet and a thread or cord attached thereto.
4. The combination of a pill or tablet, and a thread or cord embedded therein and extending beyond the outlines of the tablet.

5. The combination of a series of pills or tablets and a thread or cord passing through each thereof.
6. The combination of a series of pills or tablets and a series of threads connecting them.
7. The combination of a series of pills or tablets and a series of crossed threads con-

necting them, said threads crossing within the outlines of a pill or tablet. ¹⁰

In testimony that I claim the foregoing I have hereunto set my hand.

WILLIAM P. ROBERTSON.
